[57] CLAIM

The ornamental design of a fish scaling device, as shown and described.

DESCRIPTION

FIG. 1 is a top plan view of a fish scaling device showing my new invention;

FIG. 2 is a bottom plan view thereof;

FIG. 3 is a left side elevation view thereof, the right side elevation view being a mirrored image of the left side elevation view;

FIG. 4 is a rear elevational view thereof; and

FIG. 5 is a front elevational view thereof.

FIG. 1

FIG. 2

FIG. 3

FIG. 4

FIG. 5
